REGULATOR FOR HEATING APPARATUS,
ETC.

George F. Machlet, Elizabeth, N. J.

Application May 31, 1933, Serial No. 673,689

14 Claims. (Cl. 236—69)

This invention relates to regulators of the class disclosed in Patent No. 1,068,065 granted to me July 22, 1913, for effecting heat-regulation of furnaces and other purposes. The invention may 5 be employed where delicate regulation or control is desired.

In said patent, an element was introduced into a furnace, and connected to a galvanometer, whereby the electric current generated by the 10 heat in the element was caused to move the needle of the galvanometer, to indicate upon a scale the heat of the furnace; and when the heat reached the desired point, an automatic device co-operated with the galvanometer-needle to diminish the supply of fuel to the furnace. If the 15 heat of the furnace was lowered too far, the automatic device operated to increase the supply of fuel. Thus the heat was maintained within substantially the desired limits, with provision 20 for adjustment of the regulator.

Objects of the present invention are to simplify the construction and operation and also reduce the cost of the regulating mechanism with which the galvanometer-needle co-operates, and also to 25 obtain a more delicate regulation.

In said patent, the flow of fuel-gas into the furnace was controlled by a valve. The fuel consisted of gas mixed with air supplied under pressure. The valve itself was controlled by the 30 automatic mechanism, which depended upon the needle of the galvanometer.

In practicing the present invention, said valve is operated by variable air pressure under control of the galvanometer-needle. To obtain this 35 result, the fuel-controlling valve is operated by a piston or a diaphragm, which is mounted in an air-chamber. To this chamber air is admitted under pressure, thereby lifting the diaphragm or piston, and opening the valve to admit more 40 fuel to the furnace.

For the use of the regulator, the necessary supply of air under pressure may be obtained by simply connecting the regulator to the source of compressed air from which the furnace itself is 45 being fed. In one form of the invention, this supply of compressed air is tapped, and a nozzle is attached, from which a jet of compressed air is injected into said air-chamber, thereby increasing the pressure of air therein, and lifting 50 the diaphragm or piston, to open the fuel-control valve for the furnace.

One of the leading features of this invention is that the galvanometer-needle is made to co-operate with such a jet, to the end that pressure 55 upon only one side of the diaphragm or piston in

the air-chamber may be raised or lowered, under the control of said needle. This is accomplished by mounting a baffle in the path of the jet of air that streams from the nozzle. This baffle may be in form of a vane, which is presented edgewise to the jet and therefore offers little or no hindrance to the stream of escaping air, so that the pressure may raise and maintain the furnace-feeding valves open. The vane may swing to maintain the pressure upon the under side of the diaphragm in the air-chamber at any desired point, due to the greater or less deflecting control exercised by the vane or blade upon the constantly flowing jet.

One of the advantages of this regulatable current of air, is that such a vane, delicately mounted, so as to be movable without perceptible friction, may be operated by a connection made directly from the galvanometer-needle to the regulating vane, so that any movement of the needle 15 will cause a movement of the vane, and so vary the pressure that is being maintained against the under side of the diaphragm in the air-chamber by the jet, thus causing corresponding proportional movement of the fuel-supply valve. It is 20 of value and importance that the vane can be moved and the regulation thereby effected, without the necessity of overcoming an appreciable obstacle to the movement of the needle, whereby the weak electric galvanometer current is 25 enabled to positively and delicately control the voluminous flow of compressed air mixed with fuel-gas into the furnace. The diaphragm is self-returning, and drops in response to the deflection 30 of the air-jet effected by the swinging of the vane. 35

Another feature of the invention is the adjustment whereby the automatic operation or control of the fuel-supply valve may be set to occur at any desired point in the path of the needle. The adjustable portion of the mechanism is made to 40 be rotatable co-axially with the needle of the galvanometer, so that the effect of the needle upon the regulator will be the same at all adjustments of the regulator.

Other features and advantages will hereinafter 45 appear.

In the accompanying drawings, Figure 1 is a sectional diagrammatic elevation showing the present improvements in regulating the heat of a furnace, the valve being shown in 50 slightly open position. In this and other views, some fragments or parts are shown in exaggerated proportion for clearness.

Figure 2 is a sectional elevation showing details of the galvanometer adjustment for prede- 55

terminating the point at which the heat is to be automatically maintained.

Figure 3 is a part-sectional plan showing a furnace-element connected in a circuit having two branches, one branch having a recording galvanometer, and the other branch having a regulator for the supply of fuel flowing to the furnace.

Figure 3a is a sectional elevation showing the baffle formed directly upon the staff of the galvanometer-coil and interposed edgewise to the path of the jet of air entering the chamber containing the bell or diaphragm, for regulating the air pressure therein, and thereby raising the diaphragm or permitting it to drop.

Figure 4 shows a sensitive or weak furnace-element, which is connected to control a photoelectric relay, the latter being connected to operate the heat-regulating deflector blade.

Figure 5 is an elevation showing the photoelectric arrangement shown of Figure 4.

In Figures 6 and 9, the parts 46, 54 are omitted, and the compressed air-jet constitutes the only source of supply of air to raise the bell or diaphragm.

Figures 7 and 8 show different positions of the galvanometer-controlled baffle, and different effects produced thereby in obstructing more or less the jet of compressed air which flows into the leak in the bell-chamber, to raise the air-pressure therein, and thereby open the fuel-valve.

The furnace whose heat is to be regulated, indicated at 20, is usually provided with Bunsen burners 21 supplied from a main 22 through which flows mixed air and gas under pressure, from a carburetor or mixer 23 of the Venturi type. The air is supplied to the mixer under pressure through a pipe 24, and the fuel-gas is drawn into the mixer from a supply 25.

The flow of compressed air through the furnace-supply pipe 24 is regulated by a balanced valve that rises and falls within a head 26. There is pressure mounted in said head a central upright valve-stem 27 provided with upper and lower valves 28, 29 to open and close upper and lower horizontal ports 30, 31 provided in a cylindrical chest 32. Said ports are formed in partitions which divide the chest into top and bottom chambers separated by a middle chamber. Compressed air, under the control of a hand-valve 33, enters through a pipe 34 into the middle chamber 35 of the valve-chest and passes through the upper and lower ports 30 and 31. The rate of flow depends upon the extent to which the valves 28, 29 are opened. From the upper and lower chambers the compressed air flows through outlet-ports 36, 37 into pipe 24 on its way to the mixer 23 and the furnace 20. It is only necessary to regulate the air-supply in order to control the heat of the furnace, because the air in passing through the mixer 23 will pick up a suitable proportion of fuel.

The automatic heat-regulator includes an element 38 inserted in the furnace and forming part of an electric circuit 39. Also included in said circuit is a galvanometer 40, having a needle 41 fixed upon spindle 42, pivoted for the usual movements and carrying the usual coil 43. The needle 41 co-operates with a scale 44 to indicate the heat of the furnace. This galvanometer controls the extent to which the air-feeding ports 30 and 31 are opened by the valves; and the novel means whereby this result is accomplished forms one of the main features of the present invention, which

is useful for various regulating purposes besides controlling furnace-heat.

A weak electric current flowing through the element circuit 39 is made to control the opening and closing of the compressed air valve 28, 29, through the operation of the galvanometer-needle 41; the invention being effective for this purpose without incurring the necessity of placing an obstacle in the path of the delicate needle, or appreciably checking its progress when impelled by the weak electric current.

The regulatable power for raising the valve 28, 29 is illustrated as being derived from compressed air in the supply-main 34, from which a branch pipe 45 extends down to a conduit 46, which leads into a pocket 47, in which pressure of air received from 46 may consequently be maintained; and from this pocket extends a lead 48 that opens at 49 beneath an air elevated and supported bell 50, that is movable up in the head 26 (the latter having an air-vent 51), accordingly as the pressure in 47 is raised. Reduction of air-pressure beneath the bell, permits it to drop. The bell is sealed by means of a mercury seal 52, the mercury occupying the lower part of an annular space 53 within the head 26, surrounding the chest 32. The compressed air rising through the lead 48, flows in beneath the bell, and lifts the same, thereby raising the valve-stem 27 and the valves 28, 29 thereon, thus opening the ports for the passage of a volume of compressed air from the main 34 to the mixer 23 and the furnace. The movements or positions of the self-returning bell depend upon the fluctuation of air-pressure which in this way may be maintained under the bell. If the pressure in the pocket 47 varies up or down, then the valves 28, 29 are opened or closed, and thus the supply of air and fuel to the furnace is controlled, whereby the heat of the furnace may be regulated.

The pressure in the pocket 47 may in some instances be manually regulated by a valve 54, Figure 1, to suit different kinds or conditions of work. The pressure of air in said pocket 47 and pipe 48, and hence in the bell-raising chamber 55, is also placed under automatic control. There is employed a pneumatic device controlled by the galvanometer-needle 41 in the circuit 39.

The pneumatic portion of the automatic controller may include a branch 56 extending from supply-pipe 45, and terminating in the form of a nozzle 57, having a small orifice and discharging a jet into a larger orifice 58 of a reversed nozzle 59. The latter may contain the pressure pocket 47, which is shown as forming the end of lead 48.

If the pressure in the pocket 47 is lowered by manual valve 54, it will reach a point that is less than the full-pressure discharge from the nozzle 57 (which is placed directly opposite the reversed nozzle 59 and in line therewith so as to give it efficiency in discharging the jet into the same). The air therefore from main 34 will flow down through 45 and branch 56 and nozzle 57, and into the variable pressure pocket 47, in which the air may be static, but capable of being increased in pressure by means of the jet from nozzle 57, to raise the bell 50 and the furnace-controlling valves 28, 29; the lowering of air-pressure in the pocket 47 permitting the self-returning bell to drop.

The valve 54 may stand open or closed, or at some intermediate point. If it is closed, then the pressure of the air in the pocket 47 will depend entirely upon the force of the jet of air discharging from the high-pressure nozzle 57 into the

reversed nozzle or leak 59. When the pressure in the pocket 47 has reached a maximum, then the excess air received from nozzle 57 will be dissipated into the atmosphere. The pressure in the air-supply 46 is usually maintained at a constant point.

The force of the jet from 57 is controllable by the aforesaid galvanometer-needle; and a feature of the present invention is the provision for co-operation, with the discharge-nozzle 57, of a current-deflector in the form of a needle-controlled blade 64 that may be disposed midway between the nozzles and in line with their discharge and intake openings. This blade is presented edgewise to the stream of air and is mounted to swing on a pivot 61, the axis of the pivot intersecting the axis of the jet and being longitudinal of the blade, which may have the form of a vane or feather. The pivot of the deflector, which is at right angles to the air-jet, is provided with a crank-arm 62, so that the deflector may be swung. When parallel with the jet, the blade causes a minimum of interference to the flow of air from the active nozzle, so that maximum pressure is produced in the static pocket or chamber 47, and the bell 50 is raised to its highest point, and the furnace-supply ports 28, 29 opened to their fullest extent.

By swinging the crank-arm 62, the blade 60 may be turned to deflect the stream from the jet 57 away from the intake 58, so that pressure in the static chamber 47 falls to the minimum pressure, which minimum may if desired be determined or regulated by manipulation of the manual valve 54. The self-returning bell 50 will drop gradually in proportion to the slowly falling supporting air-pressure, and the furnace-supply valves 28, 29 will correspondingly close, so that the heat of the furnace will be reduced. Said arm 62, it will be understood, needs to be swung only a trifle and may be operated with no appreciable effort, and hence may be geared directly to the needle 41 of the galvanometer, as at Figure 2, or it may be connected by means of a link of silk thread 63, Figure 1, this being flexible and allowing considerable idle movement of the galvanometer-needle between the zero point and the zone where regulation of the furnace begins. This idle movement of the needle occurs while the furnace is warming up, and while the full pressure of air below the bell is being maintained.

It is a function of the galvanometer 40 to turn the blade 64 very slightly indeed to a position which, by the described methods, will cause the correct amount of fuel to be fed to the furnace to assure a constant specific temperature. The blade 64, being mounted in the jewels 65, is so easily turned, that the slight amount of energy available from the galvanometer 40 is more than sufficient properly to operate it. The resistance offered to the moving galvanometer-coil 43 is indeed so small that the error created by it is hardly discernible, and in most cases may be neglected. It is therefore practicable to control furnace-temperature (for example) by means of an indicating galvanometer to which this device has been added.

The problem of actuating the governing blade 64 by means of the galvanometer may be solved as at Figure 2, which represents one of many methods that may be employed. The blade-actuating arm 62 moves in a plane perpendicular to that described by the needle (or the needle-extension 67) of the galvanometer. A thin silk slack thread is employed as link 63. The opera-

tion of the various units as well as their specific function in the controlling device, may now be readily understood and followed. The galvanometer, by means of the thermo-couple inserted in the furnace, indicates the temperature in the furnace, which, for example, should be kept at 1500 degrees Fahrenheit.

While the deflector is presented at an angle of a few degrees to the path of the air jet from the nozzle 57, the air streaming from said nozzle is directed to one side of 58, and therefore may not overcome the current of air of lower pressure, which therefore vents from the reverse nozzle 59. However, if the baffle-blade takes a position substantially parallel with the nozzle 57, as in Figure 8, 15 the resistance of the baffle to the stream of high-pressure air becomes negligible. The force of the jet of air from the nozzle 57 checks the air venting from the reverse nozzle 59, and eventually overcomes the primary pressure in 59 and forces its 20 way into said nozzle, as indicated by arrows in Figure 7, and serves to raise the pressure in the bell-lifting chamber, and to raise the bell and valves 28, 29. It will be understood that the force of the jet from 57 proportionally increases 25 as the blade is swung toward its horizontal position (Figure 7), so that the pressure in the air-pocket 47 correspondingly increases.

It has been seen that this varying pressure caused by the turning of the blade 64 is utilized 30 for raising the furnace-feed valve 28, 29. The amount of air passed through the mixer 23 is governed by the position of valve 28, 29, and, by reason of the Venturi arrangement in the mixer 23, the supply of fuel-gas picked up by the air 35 will vary proportionally, as will be understood by those skilled in the art.

In Figures 6 and 9 the leftward directed arrows indicate the passage of air from jet 57 when the valve 54 is entirely closed, or when the pipe 40 46 is omitted, which may be done in some cases. Venting is not maintained from the reverse nozzle or leak 66, in which the air is originally at atmospheric pressure. When the deflector 64 is in position at Figure 9, the full force of the 45 jet from nozzle 57 is exerted in raising the pressure in the nozzle 66 (which is cut off from supply 46), as at Figure 9. Turning the deflector has the effect of more or less dissipating the jet of air discharging from 57, so that previously raised 50 pressure in 66 may vent (see arrows at Figure 6), and decline to atmospheric pressure.

From the foregoing it will be seen that the movements of the galvanometer-needle are communicated to the deflector, and the changes in 55 the position of the baffle cause variations in the pressure in the bell-chamber 26, due to greater or less dissipation of the air discharged through the nozzle 57, and the bell is raised or self lowered accordingly, thereby increasing or reducing 60 the flow of air and fuel to the furnace.

If the regulation of the furnace in some cases should admit of the nozzle 57, 59 being of equal diameters, relatively low primary pressure in the chamber 47 could be secured by means of the 65 manual valve 54. However, in the preferred practice, the orifice in the delivery jet 57 may be one-half of the diameter of the receiving orifice or leak in the reverse nozzle or jet 59. In some cases the delivering orifice may be larger, say three-fourths of the diameter of the receiving orifice or leak.

The nozzle 57 of course delivers air at higher pressure than the primary pressure which prevails in the receiving nozzle 59. For example, 75

the pressure in 57 might be fourteen inches of water-column, while the pressure in nozzle 59 will be half as much.

Other valve operating means, such as flexible 5 diaphragms, bellows, etc., may be employed.

The nozzles may be spaced apart approximately one quarter of one inch, and the width of the blade 64 may be about three thirty-seconds of an inch, say twice the diameter of the receiving 10 orifice in the reverse nozzle 59.

It is a function of the galvanometer to turn the blade 64 to a position which will cause the fuel to be fed to the furnace at such a precise rate as to assure a constant temperature within 15 the furnace, which is a desideratum for many classes of work. Said baffle 64 because of its jewels 65 is so easily turned that the slight energy available from the galvanometer is sufficient to operate the deflector. The resistance which the 20 deflector offers is indeed so small that the error created by it is hardly perceptible and is negligible.

If it is desired to keep a temperature of 1500 25 degrees Fahrenheit, for example, the arm 62 is so adjusted rotatively about the pivot of the indicating needle that the arm will not come into operating engagement with the needle until a temperature of say 1496 degrees has been reached. This adjustment is effected by rotating the turntable 68, which is mounted in a boss 69 which rises from the top of the galvanometer-casing 40, Figure 1. A boss or hub 70, on the underside of the turntable 68, fits upon the stud 69, so as to permit rotation of the turntable in either direction; and a thumb-screw 71 may fasten the turntable when the proper adjustment has been reached, Figures 1 and 2.

A pointer for aid in adjusting the head 68 about the stud 69, is indicated at 71^a, in position to co- 40 operate with scale 44.

After the described rotative adjustment has been made, the temperature of the furnace rises to the point of beginning the regulating operation at 1496 degrees. The heat of the furnace 45 continues to rise, and the needle 41 turns the arm 62 and causes the blade 64 to stir from its horizontal or maximum position, and thereby cause the current of air from the jet 57 to be deflected slightly, without opposing the swinging action 50 of the blade thus permitting the pressure in 47, 46 to fall a little, thus lowering the air-pressure in the pipe 48 and the bell-supporting chamber 50, so that the self-returning bell descends a little, and the balanced valves 28, 29 close a little, 55 thereby diminishing the supply to the furnace of air mixed with fuel. A variation of but 6 degrees Fahrenheit may be sufficient to move the valves from extreme open to extreme closed positions. Hence the temperature of the furnace 60 cannot rise above the desired 1504 degrees Fahrenheit, because at this temperature the fuel-supply is cut to its minimum.

It will be understood that as the temperature of the furnace rises above the lower limit 1496, 65 the fuel-supply is smoothly and proportionally reduced little by little until no further rise of temperature occurs. It is noted that the reduction in temperature is not effected, step by step, but gradually, without irregularity, and there is 70 absence of jerky motions.

A slight drop in temperature of the furnace will cause a retraction of the galvanometer-needle and bring about an immediate proportional rise in the amount of mixed air and fuel flowing into 75 the furnace.

It is evident therefore that after a short time of wavering, a position of the indicating needle will be found, or said needle will come to rest at such a point that will cause the exact volume of fuel to be fed to the furnace that will neither raise or lower its temperature. This position must correspond to a temperature which lies at some point between 1496 and 1504 degrees Fahrenheit in this illustration, since at 1496 the maximum amount of fuel is delivered to the furnace, thereby causing a rise in temperature, while at 1504 the minimum fuel is supplied, thereby causing a fall in temperature.

Since 1500 is midway between said two limits, 15 it may be assumed that this signifies the temperature at which the furnace will be maintained. It is of course possible that this temperature may fluctuate one degree above or below the exact point desired, but this minute inaccuracy may be entirely disregarded for all practical purposes. 20 In practice, it is found that after the temperature has reached the desired point, the graph that is produced by the galvanometer-recorder will be in the form of a straight line for an indefinite time, inasmuch as the fluctuations of the galvanometer-needle are too slight to be perceptible. It is noticed that the water-column will rise and fall several inches without any perceptible movement of the galvanometer-needle, thus illustrating the 25 delicacy of the control effected by this invention 30 over the furnace-heat.

At Figure 3a is shown, in sectional elevation, a simple form of the invention in which the baffle is provided upon the staff of the galvanometer-needle 41. Its coil is seen at 43, and the scale at 35 72. At Figure 1, the usual staff 42 carries the coil 43, but at Figure 3a the staff is marked 73, and it is formed at its upper end with extension 74, this portion being flattened to form a deflector-blade 75 corresponding with 64; the needle-staff being 40 mounted in upper and lower pivot-screws 76, 77, in supporting bracket 77^a. The deflector 75 occupies a position between the nozzle 57 and the leak or reverse nozzle 58, as at Figure 1. The 45 adjustment for a given degree of heat may be controlled by the same means as are indicated at Figure 3, in which rheostat 84 is included in the galvanometer-circuit for the purpose.

Figure 3 shows a sectional plan of one form of apparatus, in which is included in the furnace-circuit a recording galvanometer of standard construction. There is also included in the same circuit the deflector 75, which is formed upon the staff of the galvanometer-coil 43, as in Figure 50 3a. At Figure 3 the main portion of the needle 55 may be cut off, as indicated in dotted lines. By cutting off this portion a considerable reduction is effected in weight, and hence the tendency of the needle to overthrow or vibrate is minimized or overcome. The portion of the needle which is retained is indicated at 78; and there is 60 also shown the same extension-arm 79 as in other views, tending to balance the needle.

At Figure 3, electrical circuit includes the element 38 and leads 80, 81 connected to a recording galvanometer 82. From the lead 81 extends a wire 83 to connect with coil 43. Between the latter and the lead 80 is included a rheostat 84, by the use of which the temperature may be set 70 or indicated at which it is desired to maintain or control the heat of the furnace; this taking the place of the rotary adjustment at 69, 70, 71, Figure 2.

In starting the furnace according to Figure 3, 75

the rheostat may be set to offer a maximum of resistance temporarily, so that the coil 43 cannot be turned by the electrical current generated by the heating of the furnace. During such heating, 5 the needle-members 78, 79 may be temporarily set manually to a position in which the deflector 64 is presented edgewise to and parallel with the current of air from the jet, as at Figures 4 and 8. The operator may watch the galvanometer 82, 10 and as soon as the furnace is nearly hot enough, he may readjust the rheostat 84 sufficiently to cause the coil and current-deflector to co-operate automatically in the manner already explained, without further attention. The rheostat 84 is 15 adjusted until it permits just enough electric current to flow through the coil to maintain the blade in a slightly diverting working position, thereby keeping the pressure in the bell-chamber up to the point at which just sufficient fuel will be 20 steadily fed to the furnace. The rheostat 84 thus permits manual regulation of the furnace-heat.

Figures 4 and 5 show provision for using an extremely sensitive galvanometer, one that is too weak to operate the deflector 64. The weak galvanometer is made to control a delicate relay, and the relay has power to operate the deflector. The sensitive galvanometer is indicated at 85 as being connected to the element 38 (or to other source of power) by a circuit 86 which includes 30 the rheostat 84, settable to control the heat of the furnace. Galvanometer 85 includes a needle upon coil 43; this needle being broadened sufficiently at 87 so that it can cover a light-slit 88 in a cover-plate 89 of Weston photoelectric cell 90.

The light from a bulb 91 shines through the slit 88, producing a degree of electromotive force far beyond what could be directly produced by the element 38 (or other weak source). When the furnace is warmed up, the needle 87 may cover the slit 88, thus causing a fluctuation in the electric current which flows through a circuit 92 to galvanometer 93. To the needle of the latter is attached the deflector 64, as explained in connection with Figure 3, this deflector controlling escape of air from the leak 58, or the supply of compressed air from 57, in order to control the heat of the furnace, as above set forth. It will be seen that this device can 50 control variables which are measured by means of galvanometers or other instruments, which have still less available energy than that which is usually available from a good thermo-couple. The improvement may also be used in connection 55 with a regulator or adjusting mechanism to be controlled by a magnetic compass, which of course has not enough energy to operate the blade 64.

There will be seen at 90 the well-known Weston photronic cell, which, upon being adequately illuminated, generates an electromotive force which is approximately twice that which is produced by an electrothermic couple. This electromotive force is proportional to the amount of light that falls upon the photronic cell, through slit 88 in light-tight housing 89.

The broadened needle 87 moves in a plane which will enable it to cover the slit, thereby 70 shielding all light from the cell. The parts are so placed that when the furnace has reached the desired temperature, the broadened needle 87 will cover half of the slit 88. This tends to operate the deflector 64 in a way to diminish the 75 supply of fuel to the furnace 20 (or to effect the

desired control of other apparatus than furnaces). Since the indicator-needle 87 has only to intercept a beam of light, it is not retarded by so doing, or by moving the baffle 64.

The force of the electric current in the coil-circuit 39, depends upon the degree of heat in the furnace, in the present illustration of the invention. Whether the invention is applied to this or to any other regulatable apparatus, it will be understood that the fluctuations which it 10 is desired to regulate, whether in the heat or any other condition, are caused to vary the force of the current flowing through the coil 43, thereby actuating the coil. It will further be seen that the movements of the coil so caused are 15 communicated to the governor-vane 64, resulting in more or less direction of the air-jet from 57, with consequent lowering or raising of air pressure in the bell-chamber and depression or elevation of the bell. This is caused to effect regulation in the heat or other condition of the apparatus to be regulated.

The deflector, however, may turn too far, causing too great decrease in heat or other condition of the regulated apparatus; but this will cause a 25 reverse fluctuation in the coil-circuit, and thereby turn the coil a little in the opposite direction, causing a corrective increase in the heat or other condition of the apparatus. There may then be some degree of over-correction, which 30 will cause another reverse shift of the baffle, and so on; but these baffle shifts are all self-corrective, and with every movement the extent of shifting lessens, resembling the tendency of 35 the vibrations of a pendulum to diminish and cease. The baffle-mechanism may be self-corrective to such an extent that eventually it may come to rest at a point of equilibrium. The governor is therefore self-equilibrating, and is 40 distinguished from regulators in which bounds are set to the vibration of a galvanometer-needle, and in which an altering mechanism is brought automatically into action by reason of the conclusion of the needle stroke in each direction. In 45 such former regulators, the heat or other condition was not brought to one point and caused to remain there, but the condition was caused to alter a little but repeatedly so long as the operation of the furnace or other apparatus was 50 maintained. It was incessantly stepped up and stepped down; but by the present invention the deflector makes but a few self-limited shifts or vibrations before it reaches its point of equilibrium, where it remains without anything further, and no stepping mechanism is found to be 55 necessary.

Variations may be resorted to within the scope of the invention, and portions of the improvements may be used without others.

Having thus described my invention, I claim:

1. The combination with a furnace and a heat-regulating valve to control the flow of compressed air and fuel to the furnace, of a bell connected to said valve and enclosed in an air-chamber, 65 means being provided for constantly supplying compressed air to said chamber to lift and support said bell, an electric circuit including an element in said furnace and also including a galvanometer, said chamber having a leak, through 70 which the compressed air supplied to said chamber may escape, an independent jet of compressed air flowing through a nozzle into said chamber through said leak, and a blade swingable by said galvanometer and interposed in the path of 75

said jet and presented edgewise thereto, to vary its efficiency.

2. The combination with a furnace and a heat-regulating valve to control the flow of compressed air and fuel to the furnace, of a self-returning bell connected to said valve and enclosed in an air-chamber, said chamber having a vent above said bell, means being provided for supplying compressed air to said chamber but only below said bell, a galvanometer-circuit including an element in said furnace, a jet of compressed air flowing through a nozzle and into said chamber through an intake, and a deflector turned by means of said galvanometer and in the form of a blade interposed edgewise to and in the path of said jet, to deflect said jet clear of said intake.

3. The combination with a furnace and a heat-regulating valve to control the flow of mixed air and fuel to the furnace, of a diaphragm connected to said valve and enclosed in an air-chamber, an electric circuit including an element in said furnace and also including a galvanometer, means for directing a jet of air into said chamber to raise the air pressure therein sufficiently to operate said diaphragm, said galvanometer having a swingable deflecting blade presented edgewise to the jet, and an adjustable element being co-operative with said galvanometer for predetermining the point or zone of its effectiveness in regulating the flow of fuel to the furnace.

4. The combination with a furnace and a heat-regulating valve to control the flow of compressed air and fuel to the furnace, of a bell connected to said valve and enclosed in an air-chamber, means being provided for charging compressed air into said chamber, an electric circuit including an element in said furnace and also including a galvanometer, a governor operated by the galvanometer for varying the pressure of compressed air charged into said chamber, to effect corresponding closing and opening regulation of said valve, including a member carrying said governor and manually adjustable upon a fixed support about the axis of the galvanometer-needle, for predetermining the degree of furnace heat, and an index for indicating the extent of adjustment and having a scale.

5. The combination with a furnace and a heat-regulating valve to control the flow of compressed air and fuel to the furnace, of a bell connected to said valve and enclosed in an air-chamber and having a seal, means being provided for constantly supplying compressed air to said chamber to lift the bell and open the valve, a galvanometer-circuit including an element in said furnace, a jet of compressed air flowing through a leak into said chamber, and a baffle turned by means of said galvanometer and interposed in the path of said jet, to offer varying resistance to the passage of the jet into the bell-chamber.

6. The combination with a furnace and a heat-regulating valve to control the flow of compressed air and fuel to the furnace, of a bell connected to said valve and enclosed in an air-chamber and having a seal, means being provided for constantly supplying compressed air to said chamber to lift the bell and open the valve, a galvanometer-circuit including an element in said furnace, a jet of compressed air flowing through a leak into said chamber, and a baffle turned by means of said galvanometer and interposed in the path of said jet, to offer varying resistance to the passage of the jet into the bell-chamber, and

manually variable means to supply compressed air constantly to said chamber.

7. The combination with a furnace and a heat-regulating valve to control the flow of mixed air and fuel to the furnace, of a diaphragm connected to said valve and enclosed in an air-chamber, means to supply compressed air constantly to said chamber, a manually-controlled valve for controlling the supply of compressed air to said chamber, a galvanometer-circuit including an element in said furnace, and a governor operated by the galvanometer for automatically varying the pressure of air upon said diaphragm in said chamber, at all adjustments of said manual air-valve, to effect corresponding closing and opening regulation of said fuel-valve.

8. The combination with a furnace and a valve to control the flow of mixed air and fuel to the furnace, of a self-returning diaphragm connected to said valve and enclosed in an air-chamber having a leak below said diaphragm and a vent above the same, an electric circuit including an element in said furnace and also including a galvanometer having a needle, means for directing a single jet of air into said chamber through said leak, to raise the air-pressure sufficiently to lift said diaphragm, to effect opening movement of said valve, a deflector mounted in the path of said jet and presented edgewise to both said jet and said leak, and means to enable said needle to turn said deflector to direct said jet of air clear of said leak.

9. The combination with a furnace and a heat-regulating valve to control the flow of compressed air and fuel to the furnace, of a bell connected to said valve and enclosed in an air-chamber, said chamber having a leak, means being provided for supplying compressed air to said chamber, a galvanometer-circuit including an element in said furnace, a jet of compressed air flowing through a nozzle and through said leak into said chamber, and a baffle turned by means of said galvanometer and in the form of a blade interposed in the path of said jet, to offer varying resistance to the passage of the jet into the chamber, the diameter of nozzle through which the jet is discharged being substantially less than the diameter of the receiving orifice for said jet.

10. The combination with a furnace and a heat-regulating valve to control the flow of compressed air and fuel to the furnace, of a bell connected to said valve and enclosed in an air-chamber, flexible means being provided for charging compressed air into said chamber, a turntable upon which said charging means is mounted, an electric circuit including an element in said furnace and also including a galvanometer, and a governor upon said turntable and operated by the galvanometer for varying the pressure of compressed air charged into said chamber, to effect corresponding closing and opening regulation of said valve, said turntable being manually adjustable about the axis of the galvanometer-needle, for predetermining the degree of furnace heat.

11. The combination with a furnace and a heat-regulating valve to control the flow of mixed air and fuel to the furnace, of a self-returning diaphragm or bell connected to said valve and enclosed in an air-chamber, an electric circuit including an element in said furnace and also including a coil, means for supplying a jet of air to raise said diaphragm, and an air-current deflector in the form of a blade presented edgewise to the jet and mounted upon the axis of

5 said coil to turn therewith, for varying the pressure of air upon only one side of said diaphragm in said chamber to effect corresponding closing and opening regulation of said valve, said circuit also including a separate galvanometer for reading, and the coil having a rheostat for determining the degree of heat to be attained by the furnace.

10 12. The combination with a furnace and a heat-regulating valve to control the flow of compressed air and fuel to the furnace, of a diaphragm connected to said valve and enclosed in an air-chamber, means being provided for constantly supplying compressed air to said chamber to lift the diaphragm and open the valve, a galvanometer-circuit including an element in said furnace, a relay operated by the galvanometer in said circuit, a jet of compressed air flowing through a leak into said chamber, and a baffle turned by means of said relay and interposed in the path of said jet, to offer varying resistance to the passage of the jet into the diaphragm-chamber.

15 13. The combination with a furnace and a heat-regulating valve to control the flow of compressed air and fuel to the furnace, of a diaphragm connected to said valve and enclosed in an air-chamber, means being provided for constantly supplying compressed air to said chamber 20 to lift the diaphragm and open the valve, a

galvanometer-circuit including an element in said furnace, a relay operated by the galvanometer in said circuit, a jet of compressed air flowing through a leak into said chamber, and a baffle turned by means of said relay and interposed in the path of said jet, to offer varying resistance to the passage of the jet into the diaphragm-chamber, said relay including a photo-electric cell having a light-slitted cover, said galvanometer having a broad needle for covering the 10 light-slit in the cover.

14. A self-equilibrating regulator including a circuit having a coil movable in response to fluctuations in an electric current that are caused by variations in the condition of the apparatus to be regulated, a self-returning diaphragm movable in response to fluctuations in air-pressure, an air-inlet leading to said diaphragm, means for supplying a current of air through said inlet for producing pressure upon only one side 20 of said diaphragm, a deflector presented edge-wise to said current and swingable to vary the direction of flow of the current sufficiently to clear said inlet, said deflector shiftable by said coil, said diaphragm being responsive to variations in the air-pressure thereon due to swinging of said deflector, and means operated by said diaphragm to control the condition of the apparatus to be regulated.

GEORGE F. MACHLET. 30
